UNITED STATES PATENT OFFICE.

CHARLES F. W. THOMAS, OF OMAHA, NEBRASKA.

AUXILIARY STACK-GUIDE FOR PAPER-CUTTING MACHINES.

1,251,454.

Specification of Letters Patent. Patented Dec. 25, 1917.

Application filed March 19, 1917. Serial No. 155,857.

To all whom it may concern:

Be it known that I, CHARLES F. W. THOMAS, a citizen of the United States of America, residing at the city of Omaha, and county of Douglas, and State of Nebraska, have invented a new and useful Auxiliary Stack-Guide for Paper-Cutting Machines, of which the following is a specification.

This invention relates to improvements in auxiliary stack guides for paper cutting machines.

The object of the invention is to provide a removable guide which is adapted to be placed against the usual stack guide or follower of a paper cutting machine, and beneath the vertically movable stack clamp, after the said follower has been moved forward adjacent to or against the said stack clamp, the said guide having downwardly swinging, spring controlled members which permit the clamp to engage the stack, while the said swinging members at the same time form a back or guide for the stack, thus permitting a stack of any width less than that of the clamp to be properly backed while being subjected to the action of the cutting knife.

Further, to provide an auxiliary stack guide for paper cutting machines, comprising a longitudinal plate having transversely arranged, spaced, spring controlled wings pivotally connected thereto at their lower ends, the wings on the right of the center of said plate being inclined toward the right, the other wings being inclined in the opposite direction, means being provided for defining the inclination of said wings under the action of their springs, said auxiliary guide being adapted to abut against the main guide or follower of the cutting machine and beneath the clamp thereof.

These objects are accomplished by the mechanism illustrated in the accompanying drawings, in which:

Figure 1, is a front view of a paper cutting machine, showing the improved guide in position thereon.

Fig. 2, is a central, vertical, longitudinal sectional view of Fig. 1, showing the improved guide in position against the main guide or follower and beneath the stack clamp, a stack of paper or card board being

shown backed against the guide in position to be clamped.

Fig. 3, is an enlarged front view of the 55 guide.

Fig. 4, is a longitudinal sectional view—full size—of a portion of the guide showing the manner of defining the upward movement of the swinging blades. And 60

Fig. 5, is a transverse, vertical, sectional view of Fig. 4, showing more clearly the blade-actuating spring.

Similar letters of reference refer to similar parts throughout the several views. 65

Referring to the accompanying drawings,—

The numeral 1 indicates the side frames of a paper-cutting machine; 2, the table thereof; 3, the cross frame which connects the upper ends of the side frames; 4, the vertically movable clamp for engaging a stack of paper; 5 and 6, the screw and hand wheel, respectively, for operating the clamp; 7, the stack guide or follower for backing and 70 positioning a stack of paper or card board; 8 and 9, the feed screw and its hand wheel, respectively, for operating the follower; 10, the cutter or knife; 11, the knife supporting frame; 12, the operating lever therefor; and 80 13, the spring mechanism for normally holding the knife frame in a raised position.

The machine above outlined, is a style of paper cutting machine in common use, and therefore, forms no part of the present invention, and is illustrated only to show the application of the improved guide, and the position occupied by the guide relatively to the clamp and follower of the paper cutting machine. 90

In paper cutting machines of this character, the face of the clamp 4, is usually between three and four inches wide, and the guide or follower 7, which forms a backing for the stack of paper, can be fed forward 95 only until it reaches the clamp, and no farther, as will be understood by reference to Fig. 2.

It will thus be seen that if it should be desired to cut a stack of paper or card board 100 of less width than the face of the clamp 4, it would be necessary to place an auxiliary guide or back, such as a block of wood or metal, against the follower 7, to form an

abutment for the stack. This method is very unsatisfactory, as the auxiliary guide must be thick enough to form a back for the stack, and yet not too thick to prevent the clamp 5 from compressing the stack sufficiently to hold it intact under the action of the cutter. As such an auxiliary back or guide must necessarily be of less thickness than the depth of the stack to be cut, in order 10 to permit the clamp to compress the stack sufficiently, it will be seen that the uppermost sheets in the stack will have no backing during the initial compression of the stack, and are therefore apt to get out of 15 alignment, and under the action of the cutter they will be still further distorted, so that many of the sheets will be unevenly cut and therefore rendered useless for the particular purpose intended.

20 The present invention completely eliminates all of these disadvantages by providing a back or guide which is positioned beneath the clamp, and which is composed of pivoted, spring controlled, inclined wings, 25 which are pressed down by the clamp simultaneously with the clamping of the stack of paper, thus forming a thoroughly effective back or guide for a stack of paper or card board of any practicable width less 30 than that of the clamp.

The improved guide comprises a longitudinal metal plate 14, of suitable dimensions, preferably about 15 inches long by 3 inches wide by $\frac{1}{8}$ of an inch thick, and a plurality of 35 transversely arranged spring controlled inclined blades or wings 15 hinged thereto in the following manner:

The plate 14 is provided along each longitudinal edge with equi-distant integral 40 lugs 16, those on one side being opposite those on the other side, and the two central lugs 17 being substantially twice the widths of the other lugs. The lugs 16 are each provided with a transverse hole, and are about 45 the same height as the thickness of the plate. The central lugs 17 are of the same height as the lugs 16, but each lug 17 has two transverse holes, as clearly shown by Fig. 3.

The wings 15 comprise metal plates which 50 are of a suitable height, and of the same width as the plate 14. These wings are provided on their lower edges with apertured lugs 18, which are adapted to fit snugly between the pairs of oppositely positioned lugs 55 16, and each plate is pivotally connected to a pair of the said lugs 16, by a pin 19, which passes through the apertures in the lugs 16 of the plate and the lugs 18 of the wing, the central lugs 17 having two wings, as shown. 60 Eight wings are preferably employed, though a greater or less number may be used if desired, and the wings on the right of the center of the plate 14, are inclined toward the right at an angle of approxi-

mately thirty degrees, while those on the left incline toward the left at a corresponding angle, the angle of inclination being defined by the bottom edges of the lugs 18, which are beveled at an obtuse angle, the beveled edges resting against the face of the 70 plate 14, as shown in Fig. 4.

The beveled edges of the lugs permit the wings to swing in the direction of their inclination, but act as stops to prevent their movement in the opposite direction, and the 75 wings are held in their normal upright positions, by coil springs 20, one end of each spring bearing against the wing, while the other end bears against the plate 14, the wing and plate being recessed to receive the 80 respective ends of the spring so as to permit the wing to be swung down flat against the plate, the space between the lugs 16 being equal to the height of the wings.

In practice, when it is desired to cut or 85 trim a stack of paper or card board of less width than that of the clamp 4, the auxiliary back or guide is placed upon the table 2 and against the main guide or follower 7, and the latter is adjusted by means of the 90 hand wheel 9 and threaded rod 8 to properly position the auxiliary guide relatively to the cutter 10. The stack S is then placed on the table and against the auxiliary guide, as shown in Fig. 2, and the hand wheel 6 95 is operated, by which the clamp 4 is moved down. As the clamp engages the wings 15 of the auxiliary guide, the said wings yield under the pressure and are pressed down, thus permitting the clamp to engage the 100 stack S, and compress the same to the required degree, and as the wings are always in contact with the stack, the said stack will be securely held and backed under the action of the cutter, thus insuring uniformity of 105 width throughout the stack from top to bottom.

The improved guide as illustrated, forms no permanent part of the cutting machine, and is not secured thereto in any way, but simply rests upon the table 2, and is only used in cutting card board and paper in very narrow widths, as above set forth, but if desired the said guide may be arranged to take the place of the main guide or follower, and thus form part of the cutting machine.

Having described my invention, what I claim as new and desire to secure by Letters Patent, is:

1. In a device of the character described, a plate having transversely arranged inclined wings pivotally secured thereto at their lower ends and of the same width as said plate, means for defining the inclination of said wings, and springs for normally maintaining their inclination.
2. In a device of the character described,

5 a plate having two unconnected groups of transversely arranged wings pivotally secured thereto at their lower ends and of the same width as said plate, said groups being oppositely inclined, means for defining the angle of inclination of said wings, and springs for normally maintaining their inclination.

10 3. In a device of the character described, the combination with a base plate, of two unconnected groups of transversely arranged wings pivotally secured thereto at their lower ends and of the same width as the plate, the right hand group being inclined toward the right while the left hand group is oppositely inclined, means for defining the inclination of said wings, and springs for normally maintaining their inclination.

15 4. In a device of the character described, the combination with a base plate, of two unconnected groups of transversely arranged wings pivotally secured thereto at their lower ends, the right hand group of wings being inclined toward the right while the 25 left hand group is inclined toward the left, the lower edges of said wings being beveled and in engagement with the plate whereby the angle of inclination of said wings is defined, and springs for normally maintaining 30 their inclinations.

20 5. In a device of the character described, the combination with a plate having pairs of apertured, oppositely arranged lugs, of wings having apertured lugs adapted to register with the plate lugs and pivot pins which pass through said lugs, said wings comprising a right hand group which inclines toward the right and a left hand group which inclines toward the left, the 35 lower edges of said wing lugs being beveled and in engagement with the plate whereby the angle of inclination of said wings is defined, and springs surrounding said pivot pins for normally maintaining their inclination, said wings having a downward swinging movement against the action of their 40 springs.

45 6. The combination with a paper cutting machine having a table, a stack guide or follower adjustably mounted in said table, and a stack clamp, of an auxiliary stack guide adapted to be positioned on said table against said follower and beneath said clamp, comprising a plate having two independent, unconnected groups of wings pivotally secured thereto at their lower ends, said groups being oppositely inclined and said wings being of the same width as the plate, means for defining the angle of 50 inclination of said wings and springs for normally maintaining their inclinations, said wings having a downward swinging movement against the action of their 55 springs when engaged by said clamp.

7. The combination with a paper cutting 65 machine having a table, a stack guide or follower adjustably mounted in said table, and a stack clamp, of an auxiliary stack guide adapted to be positioned on said table beneath said clamp and against said follower, 70 comprising a base plate having two independent, unconnected groups of transversely arranged wings pivotally secured thereto at their lower ends and of the same width as the plate, the right hand group being inclined toward the right while the left hand group is oppositely inclined, beveled portions on said wings in engagement with the plate for defining the inclination of said wings, and springs for normally maintaining 75 their inclination, said wings having a downward swinging movement against the action of their springs when engaged by said clamp.

8. A paper cutting machine provided with 80 a table and a paper clamp, a stack guide on said table arranged to fit underneath said clamp and to receive the ends of the paper, said stack guide being provided with a plurality of resiliently moving blades arranged 85 to yield under the reciprocal movement of said clamp to allow said clamp to clamp the paper against said table, said blades being of the same width as the plate and being divided into two oppositely inclined unconnected groups.

9. In a device of the character described, a plate having two independent groups of spaced transverse wings hinged thereto at their lower ends, the wings in each group being independent and unconnected, the wings in the left hand group being inclined toward the left and those in the right hand group being inclined toward the right, 100 means for defining the inclination of the wings and springs for normally maintaining 105 their inclination.

10. In a device of the character described, a plate having two independent groups of spaced, transverse wings hinged thereto at their lower ends, the space between the wings of each group equaling the height of a wing, and the wings of each group being unconnected, the wings of the left hand group being inclined toward the left, while 110 the wings of the right hand group are inclined toward the right the lower edges of said wings being beveled and in engagement with the plate thereby to define their 115 inclination and springs for maintaining this 120 inclination.

11. In a device of the character described, a longitudinal plate having a left hand group of spaced transverse wings hinged thereto at their lower ends and inclined toward the left, the lower edges of said wings being beveled and in engagement with the plate thereby to define the angle of their 125 in-

clination, said wings being unconnected and being adapted to fold down flat against the plate, and springs for normally maintaining their inclination, a right hand group of 5 similar spaced wings hinged at their lower ends to the plate and inclined toward the right, their lower edges being beveled and in engagement with the plate thereby to define their inclination, and springs for maintaining their inclination, said wings being 10

unconnected and adapted to fold down flat against the plate, the wings in each group being of the same width as the plate.

In testimony whereof I affix my signature in presence of two witnesses.

CHARLES F. W. THOMAS.
